UNITED STATES PATENT OFFICE.

GEORGE W. STANTON, OF ATHENS, TENNESSEE.

WOOD-SPLITTING MACHINE.

1,105,108.

Specification of Letters Patent. Patented July 28, 1914.

Application filed December 10, 1913. Serial No. 805,803.

To all whom it may concern:

Be it known that I, GEORGE W. STANTON, a citizen of the United States, residing at Athens, in the county of McMinn, State of Tennessee, have invented certain new and useful Improvements in Wood-Splitting Machines; and I do hereby declare the following to be a full, clear, and exact description of the invention, such as will enable others skilled in the art to which it appertains to make and use the same.

This invention relates to wood splitting machines.

The object of the invention resides in the provision of a wood splitting machine which can be readily moved from one locality to another, which will be capable of turning out a large amount of work, and which will be simple in construction, efficient in use and which may be manufactured at a comparatively small cost.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a side elevation of a wood splitting machine constructed in accordance with the invention; Fig. 2, a plan view of what is shown in Fig. 1; Fig. 3, a front view of the invention; Fig. 4, an enlarged section on the line 4—4 of Fig. 3; Fig. 5, a section on the line 5—5 of Fig. 1; Fig. 6, a section on the line 6—6 of Fig. 1; Fig. 7, a section on the line 7—7 of Fig. 1, and Fig. 8, a section on the line 8—8 of Fig. 1.

Referring to the drawings the machine is shown as comprising a frame A supported upon front and rear wheeled axles 10 and 11 respectively. The frame A includes side members 12 and 13 which support at an intermediate point thereon a motor 14 embodying a crank shaft 15 upon which latter is fixed a belt wheel 16. Supported upon the side members 12 and 13 at the forward ends of the latter is a floor 17. Rising from the floor 17 at opposite sides thereof are uprights 18 and 19. These uprights 18 and 19 converge upwardly and disposed between the upper ends thereof are plates 20 and 21

which are held in spaced relation to each other by blocks 22. The plates 20 and 21 are held in place between the uprights 18 and 19 by means of bolts 23 and a relatively large bolt 24, said bolts extending through the uprights and the plates 20 and 21. Secured to each of the uprights is a groove guide member 25 and slideable between these guide members is a head 26 having a tapered skeleton lower end 27. The head 26 is provided at each side with a tongue 28 which slidably engages in a respective groove of the guide members 25. Secured to the head 26 and projecting from the upper end thereof is a lug 29 which is embraced by and pivotally connected to the forked terminal of a link 30. Pivotally mounted between the plates 20 and 21 on the bolt 24 is a rocker arm 31 the forward end of which is embraced by and pivotally connected to the other forked terminal of the link 30. Engaged around the bolt 24 and disposed against the outer side of respective uprights 18 and 19 are draw rods 32 the lower ends of which extend through the flooring 17 and through the terminals of a beam 33 extending across the lower side of the members 12 and 13. The lower ends of the draw rods 32 have threaded thereon nuts 34 which when screwed upon the rods will engage the beam 33 and draw and firmly secure the uprights 18 and 19 in place. The uprights 18 and 19 are further strengthened by means of braces 35 which have their upper ends secured to respective uprights and their lower ends secured to the flooring 17. The uprights 18 and 19 are also connected together by cross members 36. Supported upon the flooring 17 are cross members 37 and 38, the former being disposed against the braces 35 and the latter against the uprights 18 and 19. Supported upon the cross members 37 and 38 is an upper floor 39 which is secured in place by means of bolts 40 and 41, the former passing through the upper floor, cross member 37 and a cross member 42 disposed against the lower side of the members 12 and 13, while the latter passes through the upper floor 39, and lower floor 17. Mounted upon the upper floor 39 is a bearing 43 in which is rotatably mounted a shaft 44. Fixed on the outer end of this shaft 44 is a belt wheel 45 which alines with the belt wheel 15 and is adapted to be connected therewith through the medium of a suitable belt. Fixed on the

inner end of the shaft 44 is a disk 46 to which is connected eccentrically one end of a pitman 47, the other end of said pitman being pivotally connected to the end of the 5 rocker arm 31 remote from the link 30. By this construction it will be apparent that upon actuation of the motor 14 the rocker arm 31 will be oscillated and effect a vertical reciprocation of the head 26 in the guide members 25. The lower end of the head 26 is provided with a groove 48 which receives a rib 49 of a splitting knife 50. This splitting knife has formed integral therewith shank members 51 which pass through openings in the head 26 and have threaded on their upper end nuts 52 whereby the splitting knife is securely fastened to the head. The splitting table of the machine is formed by a plurality of blocks 53 disposed upon the 10 flooring 17 and adapted to be applied and removed according to the length of the material being split.

What is claimed is:—

1. A wood splitting machine comprising 25 a wheeled body, a floor supported upon said body, uprights rising from said floor, spaced plates between the upper ends of said uprights, bolts securing said plates and uprights together, a rocker arm pivoted between the plates on one of said bolts, a head

slidably mounted on said uprights, a splitting knife carried by the head, connections between the head and rock arm whereby the 35 oscillation of the latter will reciprocate the former, and means for oscillating said rocker arm.

2. A wood splitting machine comprising a body, a floor supported upon said body, uprights rising from said floor, bolts connecting the upper ends of said uprights, a cross beam beneath said body, draw rods connected to one of said bolts and disposed against the outer side of said uprights, said 40 draw rods extending through the floor and said cross beams, nuts threaded on the lower end of said draw rods and adapted to engage the cross beam to secure and hold the uprights to the floor, a rocker arm pivoted 45 on one of said bolts, a head slidably mounted on said uprights, a splitting knife carried by the head, connections between the head and rocker arm whereby the oscillation of the latter will reciprocate the former, and 50 means for oscillating said rocker arm.

In testimony whereof, I affix my signature, in the presence of two witnesses.

GEORGE W. STANTON.

Witnesses:

G. F. LOCKMILLER,

FRANK DODSON.
